UNITED STATES PATENT OFFICE.

CHARLES PERCY READ, OF CHICAGO, ILLINOIS.

MACHINE FOR PLACING SPRINGS IN CASINGS.

1,218,314.

Specification of Letters Patent.

Patented Mar. 6, 1917.

Application filed June 26, 1916. Serial No. 106,080.

To all whom it may concern:

Be it known that I, CHARLES PERCY READ, a citizen of the United States, residing at Chicago, in the county of Cook and State of Illinois, have invented a certain new and useful Improvement in Machines for Placing Springs in Casings, of which the following is a specification.

By recent methods mattresses, chair seats, automobile seats and backs and the like are constructed by the use of a strip of sheeting having therein a plurality of coiled spring filled pockets, the spring equipped sheeting material being wound, arranged or located as desired in the manner and for specific purposes having no relationship to the present invention. Heretofore the small coiled springs which are inserted, one in each pocket, and which are, when manually manipulated slippery, have been inserted with great difficulty by hand in each pocket.

The object of this invention is to provide mechanism which may be manually manipulated, if desired, or form part of a large automatic machine whereby these springs may be readily and cheaply inserted in the cloth pockets without the operator's experiencing any of the difficulties which are always present when it is attempted to insert the springs by hand.

The invention consists in a device capable of accomplishing the foregoing objects; which can be easily and cheaply made; which is efficient in operation, and not readily liable to get out of order. It consists further in the features and details of construction which will be hereafter more fully set forth in the specification and claims.

Referring to the drawings, in which similar numerals indicate the same parts throughout the several views,

Figure 1 is a perspective view of mechanism illustrating this invention in its preferred form, wholly separated from the work which it is to perform.

Fig. 2 is a corresponding view illustrating the device in working relation to the bag in which the springs shown within the device are to be inserted.

Fig. 3 is a sectional view on the line 3—3, Fig. 1.

The preferred form of the mechanism of this invention illustrated comprises a retaining cylinder, 10, preferably, though not necessarily, provided with a door 12 hinged

at 14 within which a coiled spring 16 which is to be inserted in the pocket 18 defined by the seams 20 and 22 in the cloth 24 is to be inserted. This cylinder 10 is suitably designed for the size of the spring 16 to be used, so that a spring will readily lie within the cylinder and may be shoved lengthwise of the cylinder by any suitable means provided for the purpose. In the particular case here illustrated, the mechanism for moving the spring comprises a piston 26 mounted upon a piston rod 28 extending from the adjacent ends of the cylinder, this piston rod being, if desired, guided in suitable cross-members 30 and 32, though these may be wholly omitted if desired so that the entire piston and piston rod may be removed from the cylinder at the right hand end, as shown in the drawing, for the insertion of the spring 16 through that end of the cylinder instead of its being put in through the opening which is closed by the door 12.

The piston rod 28 may be reciprocated in the piston by the manual operation of the user of the device, or suitable mechanism forming no part of the present invention, may be supplied to reciprocate it. Again, a single tube device and attached parts may be used, or a plurality may be placed side by side for either successive or simultaneous operation to place the springs in a plurality of pockets in the cloth device to which they are to be applied, without departing from this invention.

Extending from the forward or left hand end of the cylinder 10 as viewed in the figures, are a plurality, in the particular case here illustrated four, long flexible fingers, 34, 35, 36 and 37, made of some sort of spring material and so shaped that, as shown in Fig. 1, they normally converge together into a common point or conical top 38 of very much smaller cross-section than the cross-sectional area of the tube 10 and the spring 16 with the result that this cone shaped device made of these four spring members may be very readily inserted inside of the pocket 18 in the cloth which is to be spring filled, or into the position of Fig. 2 of the drawing.

At suitable points on the circumferential end of the tube 10 are provided means for holding the open end edge of the cloth 24 to the end of the cylinder when the parts are in the position of Fig. 2. In the par-

ticular case here illustrated, sharp hooks 40 are provided on the top of the cylinder onto which the cloth 24 is hooked, as shown in Fig. 3.

5 In order to fill in spaces between the adjacent spring members, 34, 35, 36 and 37, which exist particularly in proximity to the left hand end of the cylinder 10 intermediate spring members, such as 42 and 44, are provided. For convenience of illustration these are only shown in the drawings applied to the lower half of the cylinder, but corresponding members are, preferably in practice also applied to the upper half of 10 the cylinder, thus producing a cone of long and short spring members without openings in the sides of the cone of sufficient area so that the cloth 24 of the pocket 18 cannot readily get inside the cone and thus interfere with the operation of the piston 26 inside the cone in the manner to be herein-after described.

20 In the operation of the device, assume that the parts are in the position shown in Fig. 1. The operator now inserts a spring 16 in the cylinder 10 and at the left of the piston 26, closes the door 12 and inserts the conical end of the device in the pocket 18. In ordinary practice the cylinder 10 is stationary and the pocket 18 is applied 25 over the cone and hooked thereto. The parts are now in the position shown in Fig. 2. The operator now pushes upon piston rod 28 to move piston 26 to the left, as shown in the drawings. This movement of the piston first compresses the spring and then forces it bodily out of the cylinder 10 and into the pocket 18, in so doing distending the springs 34-37 and 42-44 from 30 conical position to cylindrical position. These spring members just enumerated sufficiently resist the movement of spring 16 by piston 26 to this new position so that spring 16 is always under control and can- 35 not do anything but move to the position desired in pocket 18. When the piston has, in carrying out this operation, been moved to a position substantially to the left of the end of cylinder 10, the operator moves pis- 40 ton rod 28 to the right, thus withdrawing the piston 26 into the cylinder 10. This allows the spring 16 to expand to substan- 45 tially the position shown at 16^a (Fig. 2), but said spring 16 is still retained inside 50 of the springs 34-37 and 42-44. The operator now unhooks the cloth 24 from the hooks 40, and preferably placing one hand 55 upon the spring 16^a which is now in the pocket and covered with the cloth 24, pulls 60 the spring and cloth off from the device.

65 It will, of course, be understood that the details of the device may be varied within reasonable limits without departing from this invention.

Having thus described my invention,

what I claim as new and desire to secure by Letters Patent, is:—

1. In a device of the class described, a spring retaining receptacle, an ejector for a spring, movable in said receptacle to 70 drive the spring out of an opening in said receptacle, and frictional means adjacent to the opening in the receptacle adapted to control the action of the spring in the receptacle as it moves therefrom. 75

2. In a device of the class described, a cylindrical member adapted to receive a spring, means movable in the cylindrical member to eject a spring from one end thereof, flexible spring fingers extending 80 from the said end of the cylinder forming normally a cone, but adapted to be expanded into a cylinder by said ejecting means.

3. In a device of the class described, a 85 hollow cylinder open at one end, a piston and piston rod movable therein toward and from said open end of the cylinder, a plurality of relatively long spring fingers extending from the open end of the cylinder 90 converging together at their outer end, and means for attaching the open end of a cloth pocket placed over said spring fingers to the end of the cylinder, for the purposes set forth. 95

4. In a device of the class described, a hollow cylinder open at one end, a piston and piston rod movable therein, and a cone made of a plurality of long and a plurality of intermediately placed short spring 100 fingers attached to the open end of the cylinder, for the purposes set forth.

5. In a device of the class described, a hollow cylinder open at one end, a piston and piston rod movable therein, and a cone 105 made of a plurality of long and a plurality of intermediately placed short spring fingers attached to the open end of the cylinder, and means for securing the open end of a pocket over said cone, for the purposes 110 set forth.

6. In a device of the class described, a cylinder open at one end, a piston and piston rod movable in said cylinder, a door in the side of the cylinder closing the opening through which a spring may be inserted inside the cylinder, means for securing the open end of a pocket to be spring filled to the open end of the cylinder, and means frictionally resisting the ejection of the 120 spring from the cylinder by said piston. 115

7. In a device of the class described, a cylinder open at one end, a piston and piston rod movable in said cylinder, a door in the side of the cylinder closing the opening 125 through which a spring may be inserted inside the cylinder, means for securing the open end of a pocket to be spring filled to the open end of the cylinder, a cone made of a plurality of flexible spring fingers ex-

tending from the open end of the cylinder, and means for attaching the open end of a pocket into which said cone is inserted to the end of the cylinder, for the purposes set forth.

5 In witness whereof, I have hereunto sub-

scribed my name in the presence of two witnesses.

CHARLES PERCY READ.

Witnesses:

DWIGHT B. CHEEVER,
M. S. ROSENZWEIG.

DISCLAIMER.

1,218,814.—*Charles Percy Read*, Chicago, Ill. MACHINE FOR PLACING SPRINGS IN CASINGS. Patent dated March 6, 1917. Disclaimer filed December 5, 1927, by the assignee, *Simmons Company*.

Disclaims from the scope of each and all of the claims of said patent, any machine except such as is used to insert into a strip composed of a series of connected open-ended parallel cloth pockets, wire springs having a plurality of co-axial spaced convolutions of diameter substantially fitting the pockets, and

Limits the scope of each and all of the claims of said patent to machines such as are used to insert into a strip composed of a series of connected open-ended parallel cloth pockets, wire springs having a plurality of co-axial spaced convolutions of diameter substantially fitting the pockets.
